CLAIM

The ornamental design for an attachment for an electrical cable, as shown and described.

DESCRIPTION

FIG. 1 is a top rear perspective view of a first embodiment of an attachment for an electrical cable;

FIG. 2 is a top front perspective view of the attachment in FIG. 1;

FIG. 3 is a top view thereof;

FIG. 4 is bottom view thereof;

FIG. 5 is a front view thereof;

FIG. 6 is a rear view thereof;

FIG. 7 is a left side view thereof;

FIG. 8 is a right side view thereof;

FIG. 9 is a top rear perspective view of a second embodiment of an attachment for an electrical cable;

FIG. 10 is a top front perspective view of the attachment in FIG. 9;

FIG. 11 is a top view thereof;

FIG. 12 is bottom view thereof;

FIG. 13 is a front view thereof;

FIG. 14 is a rear view thereof;

FIG. 15 is a left side view thereof; and,

FIG. 16 is a right side view thereof.

In the drawings, the broken lines are for the purpose of illustrating environment only and form no part of the claimed design.

1 Claim, 10 Drawing Sheets
